PLAYGROUND ROPE SWING OR THE LIKE

Vernon L. Ryan, 6802 Milliken Ave.,
Austin, Tex. 78723

Filed Oct. 4, 1974, Ser. No. 512,301

Term of patent 14 years

Int. Cl. D21—03

U.S. Cl. D34—5 M

FIG.5

FIG.3

FIG.2

FIG.4

FIG.1

FIG.6

FIG. 1 is a perspective view of a playground rope swing showing my new design;

FIG. 2 is a side view of the swing of FIG. 1, the other side having substantially the same appearance;

FIG. 3 is a front view of the swing of FIG. 1;

FIG. 4 is a rear view of the swing of FIG. 1;

FIG. 5 is a top view of the swing of FIG. 1; and

FIG. 6 is a bottom view of the swing of FIG. 1.

I claim:

The ornamental design for a playground rope swing or the like, as shown and described.
